ELECTRIC TERMINAL LUG

Howard B. Gibson, Glen Ridge, N.J., assignor to The Thomas & Betts Co., Elizabeth, N.J., a corporation of New Jersey

Application April 1, 1958, Serial No. 50,274

Term of patent 14 years

(Cl. D26—1)

Fig. 1 is a top plan view of an electric terminal lug, showing my new design;

Fig. 2 is a perspective view;

Fig. 3 is another perspective view; and

Fig. 4 is a cross-sectional view thereof, taken on line 4—4 in Fig. 1.

I claim:

The ornamental design for an electric terminal lug, as shown.
